UNITED STATES PATENT OFFICE

BURNS DICK, OF FERGUSON, MISSOURI, ASSIGNOR TO WAGNER ELECTRIC CORPORATION, OF ST. LOUIS, MISSOURI, A CORPORATION OF DELAWARE

BRAKING APPARATUS

Application filed May 16, 1932. Serial No. 611,587.

My invention relates to vehicle braking apparatus and more particularly to an improvement in band brakes of the type in which the reinforcing web has been divided intermediate the ends of the band into two spaced apart portions to decrease the initial pressure necessary to engage the band with the drum.

One of the objects of my invention is to provide a band brake of the type referred to with a radial pressure applying device acting on the band adjacent the end of the "rear" web portion and receiving its actuating force from the torque of the "forward" portion of the band.

Another object of my invention is to provide connecting means between the "forward" web portion of the band and the radial pressure applying device for the "rear" web portion that will produce an effective anchor point for the band at a point spaced ahead of the actual stop or "anchor" provided by the radial pressure applying device.

Still another object of my invention is to produce an improved radial pressure applying device for a band brake which will apply its pressure at a point closely adjacent the lining carrying portion.

Other objects will become apparent from the following description of one embodiment of my invention taken in connection with the accompanying drawing in which Figure 1 is a side elevation of a brake assembly (the drum being shown in cross section) embodying my improved brake band; Figure 2 is a cross sectional view on the line 2-2 of Figure 1; and Figure 3 is a cross sectional view on the line 3-3 of Figure 1.

Referring to the drawing, the numeral 1 indicates the drum of the brake which is secured in the usual manner to the wheel of the vehicle and is enclosed on its open side by a backing plate or support 2 secured to some fixed part of the vehicle. The brake shoe 3 is of the band type and is mounted within the drum and adapted to have its ends expanded into engagement with the drum by suitable means such as the hydraulic mechanism 4. The band is

biased to "off" position by the usual spring 5, its "off" position clearance at each end being determined by the adjustable stops 6.

The brake band 3 is of the T-section type and comprises a lining receiving flange 7 and a reinforcing web 8. The web 8 comprises two spaced apart portions 9 and 10 formed by cutting out a piece of the web at the center of the band. The lining 11 of the band is omitted over the portion of the flange that is not reinforced by the web, thus permitting a saving in lining as such portion of the flange, if covered by lining, would perform very little braking action in this type of brake.

A pair of link members 12 and 13 are pivoted at 14 to the end of the web portion 9 and extend across the cut-away portion of the web to a point beyond the end of the web portion 10 where their free ends bear 70 on the flange 7. The free ends of the links 12 and 13 are provided with inclined surfaces 15 and 16, respectively, which cooperate through a roller 17 with a pair of inclined surfaces 18 and 19 on a pair of abutments 20 and 21 positioned on opposite sides of the web portion 10 and secured to the backing plate. The abutments 20 and 21 are held in spaced relation by a suitable spacer 22. It is to be noted that the roller 17 extends through an over-size opening 23 in the web portion 10, the purpose of which is to cause the radial pressure produced by the inclined surfaces and the roller (as hereinafter described) to be applied on the band 85 at a point as close as possible to the inner surface of the flange 7.

An anchor pin 24 having bearing in the backing plate is provided with an eccentric portion 25 which extends through slots 26 and 27 in the link members 12 and 13, the slots being adjacent the end of the web portion 10 to permit the end to engage the pin 24 to anchor the band when the drum is rotating in a direction opposite to the arrow 95 (Figure 1). A flange 28 and a washer 29 on the pin prevent the links 12 and 13 from spreading apart. The eccentric portion of the anchor pin may be adjusted by unscrewing the securing nut 30 and turning the pin. 100

In order to adjust the "off" position of the central portion of the band to compensate for wear on the lining, an eccentric cam stop 31 is provided on the backing plate to cooperate with the top edges of the links.

Referring to the operation of the brake, when the hydraulic mechanism is actuated to expand the band, the initial pressure required to engage the band with the drum is 10 that required to overcome the spring 5 and to bend the flange 7 at its central portion since the ends of the web portions 9 and 10 are not restrained from relative movement, the links 12 and 13 not being secured to the 15 web portion 10. Assuming that the drum is rotating in a "forward" direction (that is to say, its direction during forward motion of the vehicle), as indicated by the arrow in Figure 1, the band, when engaged, 20 will have a slight circumferential movement with the drum, which movement will cause the links 12 and 13 to transmit the torque of the forward part of the band to the roller 23 and thereby produce a radial pressure 25 on the band adjacent the end of the web portion 10. The amount of radial pressure on the band can be varied as desired by changing the angle of the inclined surfaces.

It is to be noted that while the inclined 30 surfaces and the roller form the actual anchor for the band in the "forward" direction of rotation of the drum, the effective anchor is at the pivot 14 spaced ahead of the radial pressure device since the links 12 35 and 13 are not integral with the flange. The effective anchor at pivot 14 causes the band, when engaged with the drum, to rotate around the pivot, the portion ahead of the pivot being forced toward the drum and 40 the portion at the rear of the pivot being forced away from the drum. Since the band near the rear of pivot 14 is not provided with brake lining, the fact that it is forced away from the drum has no effect upon the 45 braking action. The forcing away of the unlined portion of the band has no effect upon the band adjacent the end of the web portion 10 as such receives a radial pressure by means of the links 12 and 13 and the 50 radial pressure applying device.

By placing the axis of the roller 17 closely adjacent the lining carrying portion of the band, the distance between the point of contact of the band with the roller and the 55 point of application of circumferential force (the lining surface), is decreased, thus decreasing the tendency of the band to rotate around the roller, which reactive effect has the undesirable result of producing a 60 distortion of the band which increases the braking pressure immediately forward of the roller and decreases it at the rear of the roller.

When the drum is rotating in a reverse direction, the band is anchored by the adjust-

able pivot pin 24 and no radial pressure is produced on the band by the inclined surfaces and the roller. By proper adjustment of the anchor pin when the band is in "off" position, the end of the web portion 10 can 70 be maintained in contact with the pin 24 and the inclined surfaces in contact with the roller, thus eliminating any "clicking" of the parts as the band is actuated to engage it with the drum in either direction 75 of rotation.

Having fully described my invention, what I claim as new and desire to secure by Letters Patent of the United States is:

1. In braking apparatus, the combination 80 of a drum, a brake band adapted to have its ends expanded into engagement with the drum, said band comprising a lining carrying portion and a reinforcing web and said web comprising two portions having spaced 85 apart ends intermediate the ends of the band, means connected to the end of one of said web portions and extending to a point adjacent the end of the other web portion, and means for applying an outward pressure to 90 the band, said pressure being transmitted through said first named means.

2. In braking apparatus, the combination 95 of a drum, a brake band adapted to have its ends expanded into engagement with the drum, said band comprising a lining carrying portion and a reinforcing web and said web comprising two portions having spaced apart ends intermediate the ends of the band, a member pivotally connected to the end of one of said web portions and extending to 100 a point adjacent the end of the other web portion, and means for applying an outward radial pressure on the band at a point adjacent to one end of said member.

3. In braking apparatus, the combination 105 of a drum, a brake band adapted to have its ends expanded into engagement with the drum, said band comprising a lining carrying portion and a reinforcing web and said web comprising two portions having spaced apart ends intermediate the ends of the band, a link pivotally connected to the end of one of said web portions and cooperating with 110 the band adjacent the end of the other web portion, and means for applying a radial pressure on the link.

4. In braking apparatus, the combination 115 of a drum, a brake band adapted to have its ends expanded into engagement with the drum, said band having a slight circumferential movement with the drum, said band comprising a lining carrying portion and a reinforcing web and said web comprising two portions having spaced apart 120 ends intermediate the ends of the band, a member connected to the end of one of said web portions and in engagement with the band at a point adjacent the end of the other web portion, and means for transfer- 125 130

ring the slight circumferential movement of the member with the band into a radial pressure on the band.

5. In braking apparatus, the combination of a drum, a brake band adapted to have its ends expanded into engagement with the drum, said band having a slight circumferential movement with the drum, said band comprising a lining carrying portion and 10 a reinforcing web and said web comprising two portions having spaced apart ends intermediate the ends of the band, a member pivoted to the end of one of said web portions and in sliding engagement with the 15 lining carrying portion of the band at a point adjacent the end of the other web portion, and means for applying a radial pressure to said member adjacent its point of engagement with the lining carrying portion 20 of the band.

6. In braking apparatus, the combination of a rotating drum, a brake band adapted to have its ends expanded into engagement with the drum, said web comprising a lining carrying portion and a reinforcing web and said web comprising two portions having spaced apart ends intermediate the ends of the band, a member connected to the end of one of said web portions and engaging 25 the band at a point adjacent the end of the other web portion, means for anchoring said band and applying a radial pressure on said link at a point adjacent the end of said last named web portion when the drum is rotating in one direction, and means for anchoring the band when the drum is rotating in the other direction.

7. In braking apparatus, the combination of a drum, a brake band adapted to have its 40 ends expanded into engagement with the drum, said band having a slight circumferential movement with the drum, said band comprising a lining carrying portion and a reinforcing web and said web comprising two portions having spaced apart ends intermediate the ends of the band, a member connected to the end of one of said web portions and in engagement with the band at a 45 point adjacent the end of the other web portion, said member being provided with an inclined surface adjacent its point of engagement with the band, a fixed abutment member having an inclined surface, and a roller in rolling contact with said inclined 50 surfaces.

8. In braking apparatus, the combination of a drum, a brake band adapted to have its ends expanded into engagement with the drum, said band having a slight circumferential movement with the drum, said band comprising a lining carrying portion and a reinforcing web and said web comprising two portions having spaced apart ends intermediate the ends of the band, a pair of 65 members pivoted to the end of one of said

web portions and in engagement with the lining carrying portion of the band at a point adjacent each side of the end of the other web portion, each of said members being provided with an inclined surface adjacent its point of engagement with the band, a fixed abutment member on each side of the last named web portion and provided with an inclined surface, and a roller in rolling contact with said inclined surfaces. 70

9. In braking apparatus, the combination of a drum, a brake band adapted to have its ends expanded into engagement with the drum, said band having a slight circumferential movement with the drum, said band comprising a lining carrying portion and a reinforcing web and said web comprising two portions having spaced apart ends intermediate the ends of the band, a member connected to the end of one of said web portions and in engagement with the band at a point adjacent the end of the other web portion, means for anchoring said band and applying a radial pressure on said member at a point adjacent the engagement of the 80 member with the band when the drum is rotating in one direction, said means comprising an inclined surface on the member, a stationary inclined surface and a floating roller in rolling contact with said surfaces, 85 and adjustable means for anchoring the band when the drum is rotating in the other direction, said adjustable anchor maintaining the roller in contact with the inclined surfaces when the band is in "off" position. 90

10. In braking apparatus, the combination of a support, a rotatable drum, a friction member adapted to cooperate with the drum and comprising a lining carrying portion and a reinforcing web, said member being capable of slight circumferential movement with the drum, means for applying radial pressure to said member, said means comprising an inclined surface carried by the friction member, an inclined surface carried by the support, and a roller interposed between and in rolling contact with the inclined surfaces, said roller lying between the inner edge of the reinforcing web and the lining carrying portion. 100

11. In braking apparatus, the combination of a support, a rotatable drum, a friction member adapted to cooperate with the drum and comprising a lining carrying portion and a reinforcing web, said member being capable of slight circumferential movement with the drum, means for applying radial pressure to said member, said means comprising an inclined surface carried by the friction member, an inclined surface carried by the support, and a roller interposed between and in rolling contact with the inclined surfaces, the axis of said roller in the "off" position of the band lying closely ad- 110 120 125 130

jacent the lining carrying portion of the band.

12. In braking apparatus, the combination of a support, a rotatable drum, a friction member adapted to cooperate with the drum and comprising a lining carrying portion and a reinforcing web, said member being capable of slight circumferential movement with the drum, means for applying radial pressure to said member, said means comprising an inclined surface carried by the friction member, an inclined surface carried by the support, and a roller interposed between and in rolling contact with the inclined surfaces, said roller projecting through the web and lying closely adjacent the lining carrying portion of the band.

13. In braking apparatus, the combination of a support, a rotatable drum, a friction member adapted to cooperate with the drum and comprising a lining carrying portion and a reinforcing web, said member being capable of slight circumferential movement with the drum, means for applying radial pressure to said member, said means comprising a pair of inclined surfaces carried by the friction member and lying on opposite sides of the web, a pair of inclined surfaces carried by the support and lying on opposite sides of the web in spaced relation to the first named inclined surfaces, and a roller interposed between and in rolling contact with said pairs of inclined surfaces, said roller extending through the web and provided with enlarged ends on each side of the web.

In testimony whereof, I hereunto affix my signature, this 12th day of May, 1932.
